Atty.

UNITED STATES PATENT OFFICE

FRANK CROSSLEY, OF TODMORDEN, ENGLAND

SHUTTLE PEG OR TONG

Application filed September 22, 1930, Serial No. 483,435, and in Great Britain October 9, 1929.

This invention relates to shuttle tongs, pegs, pikes or skewers for holding cops of weft for weaving, whether direct from spindles and without tubes or on paper or other tubes 5 or pirns or bobbins.

Tongs as up to the present constructed, that is with a bow spring of half round or other section wire all along the stem and fastened at the point by brazing do not adapt 10 themselves to the different bores of cops and therefore allow some cops in part or wholly to slip off when weaving, thus causing waste of weft, stoppage of looms, and inferior cloth, nor do they satisfactorily hold the 15 paper and similar tubes on which cotton, silk, whether artificial or natural, and other weft is now often wound, and large quantities of pirns or bobbins made from wood or similar material are split owing to the stems 20 of these tongs not being sufficiently yielding. Moreover the springs soon break away from the main part of the tongs and large quantities of tongs are regularly being repaired.

25 The object of the invention is to make tongs which will rarely break, to eliminate the repairing, and be so flexible in gauge as to need less effort by weavers to put cops, or tubes or pirns on to them and as to adjust themselves to any bores or cotton or other cops in general use and fit them so well from end to end and thereby hold them all along the bore in such a way for weaving as to lessen waste and to be even in taper all along the 30 stem so that weft from cops will be delivered with less variation in tension and so cause more even cloth to be woven, also to hold the tubes, pirns or bobbins firmly without damaging them.

40 According to this invention the flexibility, spring, outward pressure or expansion to give the grip required for holding the cops, tubes, pirns and the like on the tong is obtained by using thin sheet steel or other sheet or strip which may be wound round upon a stem or core or upon itself to form a scroll spring of one or less or more coils, the spring varying in width according to the length 45 of cops, or length of bores of tubes or pirns 50 it is required to hold, and being fastened by

soldering, brazing, welding, pinning, pressure or otherwise into the heads of the tongs, or the heads may be cast on the scroll or stems and so make complete tongs.

The invention will be fully described with 55 reference to the accompanying drawings:

Figs. 1, 2 and 3 are side elevations and transverse section showing solid forged stem slotted to receive the edge of the spring steel 60 strip.

Figs. 4, 5 and 6 are side elevation and transverse sections showing hollow, tubular stem slotted to receive the edge of the spring steel strip.

Figs. 7 and 8 are side elevation and perspective view showing solid forged stem with 65 spring steel strip riveted thereto.

Figs. 9 and 10 are side elevation and transverse section showing tong constructed of 70 spring steel strip wound upon itself without a stem or core in the form of a scroll spring.

Fig. 11 is an enlarged view of cup placed over point.

In the form shown in Figs. 1, 2 and 3 the scroll spring A is formed from a strip a of 75 spring steel coiled around a stem or core B. The stem or core B is forged solid of suitable taper with a slit or slot b from end to end into which the edge of the spring steel strip a is inserted and secured by welding, soldering, or brazing or by compressing the edges of the slit. The steel strip a is subsequently coiled one or more times around the stem or core B to form the required spring. The stem B may be forged as part of head C or 80 may be cast welded or otherwise secured thereto.

In the form shown in Figs. 4, 5 and 6 the scroll spring A is formed from a strip a of 85 spring steel coiled around a stem or core B, the stem or core B is formed tubular with a slit or slot b from end to end into which the edge of the steel strip a is inserted and secured being bent at right angles. The steel strip a is subsequently coiled one or more times around the stem or core B to form the required spring. The tubular stem or core B is splayed at the end at c and the head C is 90 cast upon it or the head may be made in two 95 100

parts and welded together with the splayed end of the tube B between them.

In the form shown in Figs. 7 and 8 the scroll spring A is formed from a strip *a* of spring steel coiled around a stem or core B. The stem or core B is forged solid of suitable taper with a flat *b*¹ from end to end upon which the spring steel strip *a* is secured by rivets or by welding, soldering or brazing. The steel strip *a* is subsequently coiled one or more times around the stem or core B to form the required spring. The stem B may be forged as part of head C or may be cast welded or otherwise secured thereto.

In the form shown in Figs. 9 and 10 the scroll spring A is formed from a strip *a* of spring steel A coiled upon itself without a core and is secured in a recess in the head C by welding, soldering or brazing or the head may be cast on.

In another form the stem or core may be made of two half round parts and the edge of the spring steel strip fastened between them by rivets or by welding, soldering or brazing and the strip subsequently coiled one or more times around the stem or core to form the required spring.

In another form a tube may be used split one or more times or have a relatively wide slot or slots longitudinally or otherwise the full length or shorter.

In any of the constructions described, a cap D may be placed over the end of the stem or core or over the end of the coiled spring and secured thereon to form a smooth point as shown in Fig. 11.

What I claim as my invention and desire to protect by Letters Patent is:—

1. A shuttle tong, peg, spike or skewer constructed with a forged stem formed with a longitudinal slit or slot, a spring steel strip secured therein and coiled into a longitudinal scroll spring around the stem substantially as described.

2. A shuttle tong, peg, spike or skewer constructed with a hollow tubular stem formed with a longitudinal slit or slot, a spring steel strip secured therein and coiled into a longitudinal scroll spring around the stem substantially as described.

In testimony whereof I have hereunto set my hand.

FRANK CROSSLEY.
